UNITED STATES PATENT OFFICE.

WLADISLAW KWIATKOWSKI AND HIPOLIT WIESCHON, OF ASTORIA, NEW YORK.

EXTENSION BED.

Application filed February 9, 1924. Serial No. 691,558.

To all whom it may concern:

Be it known that WLADISLAW KWIATKOWSKI and HIPOLIT WIESCHON, citizens of Poland, residing at Astoria, Long Island, in the county of Queens and State of New York, have invented certain new and useful Improvements in Extension Beds, of which the following is a specification.

This invention relates generally to beds, having more particular reference to an extension bed which may be varied in width according as it is intended for use as a single or double bed, the invention having for an object the provision of a novel and simple bed of this sort, a further object relating to the provision of a novel means for relatively adjusting the two spring sections to a common level when the bed is extended, while permitting one spring section to be projected under the other when the bed is collapsed or contracted.

For further comprehension of the invention, and of the objects and advantages thereof, reference will be had to the following description and accompanying drawing, and to the appended claims in which the various novel features of the invention are more particularly set forth.

Fig. 1 of the drawing is a central longitudinal vertical sectional view of my improved bed.

Fig. 2 is a detail transverse sectional view taken on the line 2—2 of Fig. 1.

Fig. 3 is a like view taken on the line 3—3 of Fig. 1.

Fig. 4 is a diagrammatic view showing a modified arrangement of the operating elements.

Fig. 5 is a fragmentary longitudinal vertical sectional view indicating particularly the position of the spring sections when the bed is extended.

As here embodied our improved bed comprises a pair of sectional frame elements. These sections comprise the end bars 10 and 11 for the respective sections which have a generally telescopic engagement with one another. The bars 10 and 11 are united at their remote ends respectively by the side pieces 12 and 13. The bars 10 are formed with longitudinal guide grooves 15 in which engage slidably the ends of the bars 11. The bars 10 having stretched therebetween the spring element or section 16 while a like spring section 17 is stretched between the bars 11. The respective frame sections are

mounted on legs 18 and 19. As the respective spring sections are located at the top edges of the two bars it is desirable that means be provided to enable the said sections to be brought to a common level when the bed is extended. To this end the spring section 16 is not connected directly to the bars 10 but to supplementary pieces 20 extending along the inner faces of such bars and sunk into suitable recesses in the latter. When the bed is contracted or collapsed these pieces rest freely at one end on the top of the bars 11 as shown clearly in the drawing. These ends may be connected by a bracing bar 15. At their other ends these pieces 20 are supported by means of the eccentric heads 21 of bolts 22 which are passed through the bars 10 and have lock nuts 23 thereon, and which may have squared ends 24 to receive turning tools.

To move the two bed sections toward and away from one another we provide a pair of shafts, 26 and 27 which are here shown as extending longitudinally of the bed and located one at the inner edge and the other at the outer edge of the section having the bars 10 and side piece 12. The shaft 26 is mounted in bearing elements 29 fixed to the undersides of the bars 10 at the inner ends of the latter this shaft serving as an intermediate longitudinal brace located between the two sides of the bed, and is provided with squared ends 30 for receiving a turning tool. Upon this shaft are mounted the drums 32 of which there is one near each end of the shaft, and over these drums are wound the cords 33 which connect to brackets 34 on the inner ends of the bars 11, rotation of the shaft 26 serving to extend the bed. The shaft 27 is mounted on bearing elements such as 36 by the side piece 12, and has mounted thereon a pair of drums 37 over which are wound the cords or wires 38 which extend transversely under the bed and connect to brackets 39 on the side piece 13. The shaft 27 may have squared ends 27' to receive a turning implement.

It is believed that the manner of adjustment of our improved bed will be readily understood from the above description. When the bed is collapsed and is to be extended the shaft 26 is turned to pull on the cord 33 and so extend the bed. As the latter is at the end of its extension movement the inner ends of the members 20 drop down on projections 11' on the inner ends of the

bars 11. The bolts 22, which have first been loosened are given a half turn, dropping the other ends of the members downward, the two spring sections 16 and 17 being then on a common level. When the bed is to be collapsed the members 20 are raised by hand while the shaft 27 is given enough movement to bring the ends of the bars 11 under the said members the bolts 22 are then turned to raise the other ends of the members 20 and the rotation of shaft 27 completed to bring the bed to collapsed position, the cords winding on the drums 37 as shaft 27 is rotated, and thereby drawing the sections to collapsed position.

In Fig. 4 of the drawing we have shown in diagram a modified arrangement for moving the two sections upon one another. As here shown I provide only the shaft 26 and the drums 32. Over each drum is wound a single cord 40 which is fixed to the drum midway between its ends and which connects at opposite ends to the opposite sides of the section composed of the elements 11, 13. By rotating this shaft in opposite directions the bed may be extended or collapsed.

Having thus described our invention what we claim as new and desire to protect by Letters Patent of the United States is as follows:

1. A bed comprising end bars each made up of a pair of sections, one of said sections being formed with a guide groove and the other section engaging slidably in said guide, a spring section fixed at its ends to the bars of the first named section, vertically adjustable members extending along the other bars of the other section, and a spring section fixed at its ends to the said vertically adjustable members, said vertically adjustable members resting freely on

the bars of the second named section at one end, and cam elements supporting the said members at their other ends.

2. A bed comprising end bars each made up of a pair of sections, one of said sections being formed with a guide groove and the other section engaging slidably in said guide, a spring section fixed at its ends to the bars of the first named section, vertically adjustable members extending along the other bars of the other section, and a spring section fixed at its ends to the said vertically adjustable members, said vertically adjustable members resting at one end on the bars of the second named section, bolts carried by the bars of the first named section, and eccentric heads on said bolts supporting the said vertically adjustable members at their other ends.

3. A bed comprising end bars each made up of a pair of sections, one of said sections being formed with a guide groove and the other section engaging slidably in said guide, a spring section fixed at its ends to the bars of the first named section, vertically adjustable members extending along the other bars of the other section, and a spring section fixed at its ends to the said vertically adjustable members, said vertically adjustable members resting at one end on the bars of the second named section, bolts carried by the bars of the first named section, and eccentric heads on said bolts supporting the said vertically adjustable members at their other ends, said second named bars having projections adapted to receive and support the ends of the said members when the bed is extended.

In testimony whereof we have affixed our signatures.

Wладислав Квятковский.
Hipolit Wieschon.
